UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

STIFFENER FOR CANS.

1,281,377.

Specification of Letters Patent. Patented Oct. 15, 1918.

Application filed February 12, 1915. Serial No. 7,716.

To all whom it may concern:

Be it known that I, JOHN M. HOTHERSALL, a citizen of the United States, residing in Brooklyn, in the county of Kings and State of New York, have invented a new and useful Improvement in Stiffeners for Cans, of which the following is a specification.

My present invention relates to sifter cans and more particularly to sifter cans where it is intended that the sifter top or cover merely fits tightly over the upper end of the body, without being soldered or otherwise rigidly secured thereto.

The purpose of the invention, broadly, is to provide an effective means for stiffening the upper or open end of the body, over which the sifter top or closure fits.

The invention is hereinafter described as embodied in a talcum powder box, although it will be readily understood that it is capable of embodiment in numerous other forms of boxes intended for various purposes.

The principal object of the invention is the provision of a stiffener which may be merely pushed into position, without requiring particular formation of the can or box.

A further object of the invention is the provision of such a device which will permit the easy positioning of the cover, and, at the same time, prevent its easy removal.

A further object of the invention is the provision of a device of this character which may be cheaply constructed, which will be strong and durable in use, and which will not interfere materially with the sifting of the material from the can or box.

Other objects and advantages of the invention will be better understood from the following description, when considered in connection with the accompanying drawing illustrating a preferred embodiment thereof.

On the drawing,

Figure 1 is a transverse, vertical, sectional view of a sifter can embodying my invention;

Fig. 2 is a perspective of the same with the sifter top removed; and

Fig. 3 is a similar view of the stiffener.

For the purpose of illustrating my invention, I have shown it embodied in a stiffener, 4 positioned in the open top of a talcum powder box body 5. The box body 5 is of a well known rectangular form and is provided with an outwardly pressed, encircling

bead or shoulder 6 just beneath the upper edge, against which shoulder the cover 7, having the usual sifter top 8 is adapted to seat.

The stiffening device 4 consists in the present instance of a single, metallic sheet resting at opposite edges in the depression 9, provided within the box body through formation of the bead 6.

The sheet 4 is preferably corrugated and when positioned, as seen in Fig. 2, the corrugations are disposed transversely of the box body. These corrugations perform the double function of stiffening the sheet and of producing more rigid engagements with in the depression 9. The sheet is constructed so that it fits tightly in place and has only a width sufficient to give it the desired rigidity.

When it is desired to sift powder, or the like, from the box, it is only necessary to manipulate the box in the usual manner—the customary shaking causing the powder to readily pass the stiffener.

The stiffener is placed in position by inserting one edge in the depression and springing the other side of the body away by pressure exerted on the stiffener through the depression. The materials of boxes of this character are usually resilient enough to permit this to occur. This position of the stiffener prevents depression of the sides and prevents the formation of openings between the cover and body, through which powder might spill. The cover slides easily into position, as it may be readily inserted over the open end of the body and pressed down to final position. It cannot be withdrawn nearly so easily, because of the tight engagement produced by forcing it down against the bead 6.

A stiffener of this type is only needed on a rectangular or straight sided box such as I have shown. Other shapes have comparatively rigid self-sustaining walls without requiring any additional means to stiffen them. In talcum powder boxes it is necessary that the sifter top and breast fit the top of the box very tightly all around to prevent powder seeping out during transporting and handling. This desirable tight fit is easily possible in any box having a circular or elliptical section, since a tight fitting cover simply compresses the metal all around the point of engagement and, in

ordinary handling and manipulation, it is not ordinarily possible to press in the side sufficiently with the fingers to cause a seepage of powder. I have found great difficulty, however in getting a sufficiently tight fit in straight sided boxes until I made the invention herein described.

It is readily seen that placing a tight fitting top on a straight sided box such as I 10 show simply results in drawing the four corners inward and producing a slight collapse of the sides inward to relieve the tension, with the result that heretofore, all such boxes leaked more or less. Also, the 15 straight sides are so easily flexed inward by a very slight pressure of the fingers that seepage occurs.

Since manufacturing straight sided boxes with this invention applied, all this trouble 20 has been obviated, and I am now able to make the fit of the cover tight enough, and so hold it, to prevent all seepage of powder in ordinary handling and also to make the frictional engagement and holding of the 25 cover permanent against any ordinary removing force.

In the drawings, I have shown a rectangular elongated can, which requires a brace in only two opposite directions. A square can 30 might require a brace on all four sides which could be accomplished by using a rectangular brace or stiffener touching all four sides with the four corners cut away to pass powder to the sifter top. It must be remembered that in the rapid manufacture of talcum boxes, the tops fit very tightly and are pressed home by machinery, after the boxes are filled with powder, and cannot be removed without considerable effort, in fact 35 under ordinary conditions of use they are not intended to be removed, and seldom, if ever, are. Thus, it is easily seen that many difficulties have attended the making of straight sided boxes and procuring a lasting, 40 tight and powder proof fit, between the slip joint of the box and cover, until the adoption of this device.

It is thought that the invention and many of its attendant advantages will be readily 45 understood without further description, and it will be apparent that various changes may be made in the form, construction, and application of the stiffening device, without departing from the spirit and scope 55 of the invention, or sacrificing any of its material advantages, the form hereinbefore

described being merely a preferred embodiment thereof.

I claim:

1. A box comprising a straight sided body, 60 a tight fitting, flanged cover therefor, provided with a sifter top, and a stiffener member engaging the inner faces of opposite sides of said box adjacent the meeting edges of said cover and box to prevent inward 65 flexion of said sides when said tight fitting cover is secured to the box.

2. A box comprising a straight sided body, a tight fitting cover therefor, provided with a sifter top, said box having engaging means 70 about its interior adjacent the top edge thereof, and a stiffener member engaging the inner faces of opposite sides of said box, adjacent the meeting edges of said cover and box, to prevent inward flexion of said 75 sides when said tight fitting cover is secured to said box.

3. A box comprising a straight sided horizontally elongated body comprising two long sides and two short sides, a stiffener member 80 engaging the inner faces of the opposing longer sides of said body near the open top of the same to prevent inward flexion of said sides relative to the cover and a tight fitting cover for said body, provided with a 85 sifter top, and having flanges engaging the outer sides of said body and extending down substantially to the level of the said stiffener member.

4. A box comprising a straight sided body 90 formed with a horizontal bead, a corrugated stiffener member engaging the said bead on the inner faces of opposing sides of said body near the open top of the same to prevent inward flexion of said sides relative to 95 the cover, and a tight fitting cover for said body, provided with a sifter top, and having flanges engaging the outer sides of said body and extending down substantially to the said bead, the said stiffener member 1 being arranged to permit the passage of powder to the sifter top.

5. A sheet metal can comprising a body and a flanged cover, combined with a transverse stiffener engaging the inner faces of 1 opposite sides of said can adjacent the slip joint formed between the body and cover.

JOHN M. HOTHERSALL.
